(57) **CLAIM**

The ornamental design for a safety cone broom and mop holder set, as shown and described.

DESCRIPTION

FIG. 1 is a perspective view of a safety cone broom and holder set showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of the safety cone broom and mop holder set in an alternate configuration;

FIG. 9 is a perspective view of the safety cone broom and mop holder set in an environment of use; and,

FIG. 10 is a perspective view of the safety cone broom and mop holder set in an environment of use with cleaning tools. Throughout the figures, the broken lines shown in the foldable platforms of the safety cone broom and mop holder set form no part of the claimed design. All other broken lines in FIGS. 9-10 illustrate environmental subject matter that form no part of the claimed design.
